UNITED STATES PATENT OFFICE.

ALFRED B. WALES, OF WHITMAN, MASSACHUSETTS, ASSIGNOR, BY MESNE ASSIGNMENTS, TO UNITED SHOE MACHINERY COMPANY, OF PATERSON, NEW JERSEY, A CORPORATION OF NEW JERSEY.

EYELETING-MACHINE.

1,143,741.

Specification of Letters Patent. Patented June 22, 1915.

Application filed May 4, 1912. Serial No. 695,064.

To all whom it may concern:

Be it known that I, ALFRED B. WALES, a citizen of the United States, residing at Whitman, county of Plymouth, State of Massachusetts, have invented a certain new and useful Improvement in Eyeleting-Machines, of which the following is a specification, reference being had therein to the accompanying drawings.

My invention has for its object a machine for setting what are termed "blind eyelets."

The invention is fully set forth in the following description, taken in connection with the accompanying drawings, and the 15 novel features are pointed out in the claims at the close of the specification.

What is termed a "blind eyelet" is an eyelet which is set in the under one of two pieces of sheet material, the upper piece of 20 material serving to cover and conceal the eyelet, and there being in the upper piece a hole which registers with the hole through the eyelet and thus permits the passage of a shoe lace or the like. Such blind eyelets 25 are used to a considerable extent in the uppers of boots and shoes, being set in the lining or facing stay beneath the leather or outer portion of the quarter.

Hitherto so far as known to me in the 30 setting of blind eyelets both the pieces of leather are first punched. After the punching operation is completed the upper or covering piece of leather is turned back, and the eyelets are then set in the lining or stay.

This entails a second handling of the stock 35 and is a relatively slow operation. With a view to obviating this second handling of the work and improving both the rapidity and economy of the blind eyeleting operation, an object of the present invention is to 40 provide means for alternately performing the step of punching both parts of an upper and the step of setting an eyelet in one part of the upper in the hole thus formed 45 in that part, while the two parts are maintained in the normal relation which is to be preserved in the finished shoe.

To this end, an important feature of the 50 invention is the combination of a feeding member arranged to carry a punched upper into line with an eyelet carrying set, with means acting before the feeding member is withdrawn from the upper and upon the barrel of an eyelet inserted by the set

through one portion of the upper for clinching 55 the end of the barrel upon the concealed surface of said portion.

By the employment of a machine constructed in accordance with my invention the two pieces of leather are punched and 60 the eyelets are set in the under piece as rapidly and continuously as heretofore a single strip of leather has been punched and eyelets set therein.

One important feature of the invention 65 consists in the provision of a thin work separating member adapted to be inserted between the partially attached parts of a shoe upper and serving to separate that part which is to be punched only from that part 70 which is to be punched and eyeleted. An important advantage of such a separating member is that the two parts of the upper may be fed across its opposite faces and any desired or different operations may be 75 performed independently without difficulty upon the parts of the work so separated.

In the machine herein shown an upsetting die is mounted upon one side of the work 80 separating member and a setting die is arranged to coöperate therewith for inserting and clinching successive eyelets in the part of the upper which is fed across the upsetting die. The work separating member upon its other side is made smooth so that the 85 other side of the upper, which is to be punched only, can be fed across it without obstruction.

Another important feature of the invention 90 consists in the provision of means for supporting the thin work separating member against the pressure of the setting die during the setting operation while at the same time leaving an unobstructed space for the passage of the work on both sides of the 95 separating member between the setting operations. As herein shown this is effected by arranging the punch to be moved oppositely to the setting die and to engage the smooth side of the work engaging member 100 when the setting die is moved toward the upsetting die.

Still another feature of the invention consists in so shaping the separating member 105 that it need be inserted only a short distance within the edge of the upper. Under such circumstances the separating member will not interfere with the inner line of top

stitching found in shoes of many styles, whereas otherwise, it would be necessary to set the blind eyelets before the quarter had been stitched. This would render likely inaccuracies in alinement between the holes and the eyelets when the upper and lining were finally stitched together. One form of separating member which possesses the advantage above disclosed is herein shown and

5 **10** comprises a plate having a shank portion disposed transversely to the edge of the work and a body portion extending substantially parallel thereto.

As herein shown the work separating member is utilized to strip one piece of material from the feeding member as the work is fed between the punching and setting operations. This constitutes still another feature of the invention and renders it possible

15 **20** to utilize the punch for feeding the work.

In the drawings, Figure 1 is a plan view of the attachment embodying my invention shown secured to the table of an eyeleting machine. Fig. 2 is a front view of a portion of an eyeleting machine showing my attachment applied to the table thereof, and also showing the lower set and the punch, the latter being in its highest position. Fig. 3 is a similar view showing the punch after it has cut a hole in the two strips of leather. Fig. 4 is a similar view showing the parts in the position which they occupy at the completion of the setting of the eyelet. Fig. 5 is a perspective of a piece of work showing the upper and under strips which are used in blind eyeleting, the under strip having eyelets therein, and the upper strip holes which register with the barrels of the eyelets.

40 The invention is herein illustrated as embodied in an eyeleting machine of the type disclosed in Letters Patent of the United States No. 686,928, granted on an application of P. R. Glass to which reference may be had for details not herein shown. It will be understood, however, that the invention is not limited in its application to this or any particular type of eyeleting machine.

Referring to the drawings, 2 is a part or plate formed preferably from a relatively thin flexible sheet of metal. This plate is shaped as shown in plan in Fig. 1, and is adapted to be secured by means of screws 3 or equivalent securing devices to the top of the work plate 4 of an eyeleting machine. The plate 2 comprises a body portion, and a shank portion slotted for purposes of adjustment and maintained in place by the screws 3. This shank portion is mounted upon a small plate or block 5 which serves to hold the part 2 above the table 4 so that the lining 6 in which the eyelets are to be set, may pass under the part 2 while the outer part of the quarter 7 may pass over the said part 2. Running from front to

back of the part 2 and substantially parallel with the lower edge as seen in Fig. 1, is an opening 8, through which the punch 11 may pass in perforating the two pieces of material. The opening 8 is of a sufficient length so that it will not interfere with the feed movement of the punch, and extends in the direction of the feed to and through the neck portion 10 of the part 2.

As will be clear to those skilled in the art the stock is fed forward by the punch, after each cutting movement of the latter, a distance equal to the distance between the eyelets.

The part 2 is provided with a projecting portion 9, the neck 10 of said portion 9 being bent downwardly as shown in Fig. 2 so that the punch 11 when moving forward to feed the stock will pass out of the opening 8 and over the forward projection 9. On the under side of the projection 9 is secured an upsetting die or upper set member 12 which cooperates with the set 13 of the machine, and when the punch has completed its forward feed movement it is directly over the upper set 12 as shown in Fig. 4. The forward feed movement of the punch causes the neck portion of the part 2 to disengage the under portion 6 of the upper from the point of the punch, and the engagement of the punch with the superposed portion 7 of the upper carries the leather forward until the upper setting die is located in the hole just formed by the punch in the lining. When the punch is in this position the under set 13 with the eyelet 14 in position as shown Figs. 1, 2 and 3 is moved upwardly and the eyelet is inserted and set in the lower portion 6 as shown Fig. 4, the end of the eyelet barrel being clenched upon the inner or concealed surface of the lower portion. The part 2 together with its projecting end 9 may be made of comparatively thin sheet material, because at the time the eyelet is set it is backed up by the punch and is therefore held rigidly and prevented from yielding.

After the eyelet is set the punch moves upwardly and toward the right as seen in the figures and again descends through the slot 8 cutting holes in both the upper and lower pieces 7 and 6 and again feeds the stock forward stopping directly over the upsetting die 12 on the projection 9, and another eyelet is then set in the lower portion of the upper and the operation repeated. The construction and operation of the punch, as also the lower set are well known to those skilled in the art and do not require detailed description.

125 What I have termed the block or plate 5 is located on the side of the plate 2 which is toward the top of the sheet as seen in Fig. 1, the edge of said block 5 which is next the slot being indicated by dotted line

- 15, Fig. 1 and it will be clear that said block may be either integral with the part 2 or it may be formed on the work plate of the machine and be integral therewith, or 5 it may as indicated in the drawings, be simply a separate strip or block of proper size having holes therein through which the securing screws 3 may pass. This block is not only thick enough to permit the lower 10 portions of the work to pass under the plate, but also to hold the upper portion of the work high enough up to prevent it slipping off over the end of the punch before the feeding movement is completed, and the 15 plate adjacent the slot supports the upper portion of the work on both sides of the punch during the feeding movement up to the time when the punch passes out of the slot. The curve at the neck 10 of the part 2, shown Figs. 2, 3 and 4 is sufficient to carry the projecting end 9 downwardly so that as the punch feeds forward it will pass out of the slot or opening 8 and over the upper surface of the part 9.
- 20 25 It will be noted that the punch remains in the upper during the feeding operation and is moved into line with the set 13 so that the punch, upsetting die and set are in line, the punch being in the upper and the 30 upsetting die being located between the two parts of the upper during the setting operation. This arrangement constitutes an important feature of the blind eyelet setting mechanism of my invention and has not 35 been known or used heretofore.
- My device is simple and of easy application to an eyeleting machine, and its use permits, for the first time, the entire blind eyeleting operation, that is the punching 40 of two layers of material and the inserting of an eyelet in the covered layer, to be carried out in a single machine.
- My copending application Serial No. 834,438, filed April 25, 1914, discloses a 45 novel method of producing an upper having blind eyelets set therein and certain steps of that method may be carried out with good advantage by the machine herein disclosed.
- 50 55 What I claim is:
1. In an eyeleting machine, the combination with the punch and set of an intermediate plate comprising a body portion, a projecting portion and a curved connecting neck, said neck and body portion being slotted to permit the passage of the punch and said projecting portion being provided with a setting member to cooperate with the set of the machine.
  2. In an eyeleting machine, the combination with the punch and set of a plate located permanently between said punch and set, said plate having a cooperating setting member thereon registering with the set.
3. In an eyeleting machine, the combination with the punch and set of an intermediate plate on the work table of the machine, said plate comprising a body portion, a projecting portion, and a connecting 70 curved neck, said body portion and curved neck being slotted to permit the punching and feeding movements of the punch, said neck serving to remove the lower strip in which the eyelet is to be set from the punch. 75
4. In an eyeleting machine, the combination with a punch and set of an intermediate plate adapted to project between two strips of material both of which are to be punched and in one of which eyelets are to 80 be set, said plate having an opening therein to permit the passage of the punch in the punching operation and to permit the movement of the punch in the feeding operation and having a projection provided with a co-operating setting member, said projection being located below the cutting end of the punch when the latter is feeding the stock forward. 85
5. In an eyeleting machine, the combination with the punch and set of a plate adapted to project between two strips of leather through which the punch operates, said plate being slotted to permit the passage therethrough of the punch and being so 90 shaped as to be above the cutting end of the punch where the punching operation is performed and below the cutting end of the punch where the setting operation is performed. 95
6. In an eyeleting machine, the combination with a work table, a punch and a lower set, of an apertured plate through which the punch passes in perforating the work, said plate being raised above the work table sufficiently to allow one portion of the work to 100 pass under the plate and to hold the upper portion of the work up on the punch during the setting operation. 105
7. In an eyeleting machine, the combination with a punch for punching two pieces of leather, an intermediate plate having a set on one side which may be introduced between the two pieces, and a co-operating set for setting an eyelet in one piece against the set on the intermediate plate while the punch remains in the hole in the other piece. 110
8. A machine for inserting blind eyelets in shoe uppers, having in combination, a punch member having a portion constructed 115 and arranged to perforate both the leather and the lining parts of the upper, a reciprocatory eyelet carrying set, and an upsetting die for clinching the eyelet barrel on the lining while a portion of the punch member remains in the hole in the leather part. 120
9. In an eyeleting machine, the combination with a thin set-carrying plate, means for punching and positively feeding two 125

pieces of leather, one on either side of said plate, a set carried by the plate, and a co-operating set movable to insert an eyelet in the piece of leather located on one side of the plate while the feeding means occupies the hole punched in the piece located on the other side of the plate.

10. In an eyeleting machine, the combination with a thin set-carrying plate having a shank disposed transversely to the edge of the work and a work-separating portion extending substantially parallel to the edge of the work and adapted to be inserted between two partially attached pieces of sheet material, together with a movable setting die, and means for adjustably maintaining said plate with its set in line with the movable die.

11. A machine for inserting blind eyelets in shoe uppers having, in combination, a tool with its end shaped for punching, said tool being constructed and arranged to enter a shoe upper from the outer side and to perforate both the outer portion and the lining portion, an eyelet carrying set movable toward the inner or lining side of the punched upper to insert an eyelet in said lining portion, and means for clenching the barrel of the eyelet upon the lining and beneath the outer portion of the upper before the tool is withdrawn from the upper.

12. A machine for inserting blind eyelets in a shoe upper, having in combination, a work table, a cutting block, a punch member movable toward the cutting block to perforate both the leather and the lining parts of the upper, an upsetting die arranged to occupy a position between the leather and lining parts when a portion of the punch is in the leather part, and a co-operating eyelet carrying set for inserting an eyelet in the lining to be clenched by the upsetting die.

13. In an eyeleting machine, the combination with an upsetting die, a punch movable to perforate two pieces of work at a point at one side of the upsetting die and then to feed the work into alignment with the upsetting die, and a work separating member having an inclined portion located between the upsetting die and the punching portion for stripping one piece of the work from the punch and maintaining the other piece on the punch during the feeding operation.

14. In an eyeleting machine, the combination with an upsetting die, a feeding member for advancing the work from punching position at one side of the upsetting die into alignment with said die, and a work separating member shaped to strip one of two superposed pieces of sheet material from the feeding member during the feeding operation.

15. A machine for inserting blind eyelets in shoe uppers having, in combination, a tool with its end shaped for punching, said tool being movable in the machine to enter a shoe upper from one side thereof and to perfor-

rate both the lining portion and the outer portion, an eyelet carrying set movable toward the opposite side of the upper while the tool remains in the upper for inserting an eyelet in one portion, and means for clenching the barrel of the eyelet on said portion and beneath the other portion of the upper while the tool remains in the upper.

16. A machine for setting blind eyelets having, in combination, a thin projecting member constructed and arranged to be inserted between two layers of partially attached sheet material and having an upsetting die on one side thereof and a smooth surface on the other, means co-operating with said upsetting die for setting an eyelet in one of said layers, and an independent punch for punching a hole through the other of said layers in alignment with the eyelet.

17. A machine for setting blind eyelets having, in combination, a thin die-carrying member having an upsetting die on one side and a surface of the other side shaped to facilitate the unimpeded passage of the material, said member projecting so that layers of sheet material may be moved past both sides, means co-operating with the die to set an eyelet in the layer on one side of the member, and a separate punch for punching a hole through the other layer in alignment with the eyelet.

18. A machine for setting blind eyelets having, in combination, a work separating device having an upsetting die on one side and a smooth surface on the other, means for feeding partially attached layers of sheet material past said device in a step-by-step manner, a set for setting an eyelet in one layer in cooperation with the upsetting die, and a punch for operating on the layer which engages the smooth face of the separating device.

19. A machine for inserting blind eyelets in shoe uppers having, in combination, a tool with its end shaped for punching, said tool being movable downwardly to punch both the outer and the lining portions of a shoe upper, an eyelet carrying set movable upwardly toward the upper to insert an eyelet in the lowermost portion thereof, and means for clenching the barrel of the eyelet upon said portion and independently of the uppermost portion of the upper while the tool remains in vertical line with the set and in its lowermost position.

20. A machine for inserting blind tubular fasteners in shoe uppers, having, in combination, a fastener carrying set, a punch movable vertically for punching the upper and then horizontally for feeding the punched upper from a punching position at one side of the set to a position over the set, and means for moving the set upwardly to insert a fastener in the lowermost layer of

the upper and clench its barrel beneath the uppermost layer while the punch remains in position at the end of its feeding movement

- 5 21. A machine for inserting blind tubular fasteners in shoe uppers, having, in combination, a fastener carrying set, a punch constructed and arranged for punching both parts of an upper and for feeding
10 them into position above the set, upsetting means located in line with said punch and set and between the two parts of the upper when the upper has been fed over the set, and means for operating the set, with the
15 parts of the upper in this position, to set a fastener in the under part while the punch remains in its lowermost position.
22. In a machine for inserting blind eyelets in shoe uppers comprising an outer and
20 a lining portion, the combination of a work table; an eyelet carrying set movable in a vertical path adjacent to the table; a feeding member movable over the surface of the work table to feed a punched upper, by engagement with a hole in the upper, into line with the eyelet carrying set; and means
25

which acts, before the feeding member is withdrawn from the hole in the upper, upon the barrel of an eyelet inserted by the set through one portion of the upper to clench 30 the end of the barrel upon the concealed surface of said portion.

23. In a machine for inserting blind eyelets in shoe uppers comprising outer and lining portions, the combination of a work 35 table; an eyelet inserting set movable toward an upper supported by the table; a feeding member movable to feed a punched upper, by engagement with a hole in the upper, into line with the eyelet inserting 40 set; and means which acts, while the feeding member still controls the position of the upper, upon the barrel of an eyelet inserted by the set through one portion of the upper to clench the end of the barrel upon 45 the inner surface of said portion.

In testimony whereof I affix my signature, in presence of two witnesses.

ALFRED B. WALES.

Corrections in Letters Patent No. 1,143,741.

It is hereby certified that in Letters Patent No. 1,143,741, granted June 22, 1915, upon the application of Alfred B. Wales, of Whitman, Massachusetts, for an improvement in "Eyeleting-Machines," errors appear in the printed specification requiring correction as follows: Page 2, line 97, for the word "leather" read *upper*; same page, line 98, for the words "upper setting" read *upsetting*; and that the said Letters Patent should be read with these corrections therein that the same may conform to the record of the case in the Patent Office.

Signed and sealed this 15th day of February, A. D., 1916.

[SEAL.]

R. F. WHITEHEAD,

Acting Commissioner of Patents.
